UNITED STATES PATENT OFFICE.

ARLINGTON A. BLOUNT AND CHARLES M. PADULA, OF WORCESTER, MASSACHUSETTS,
ASSIGNORS TO WORCESTER SHOE MACHINERY COMPANY, OF WORCESTER, MASSA-
CHUSETTS, A CORPORATION OF MASSACHUSETTS.

POLISHING-WHEEL.

1,119,743.

Specification of Letters Patent.

Patented Dec. 1, 1914.

Application filed November 14, 1910. Serial No. 592,159.

To all whom it may concern:

Be it known that we, ARLINGTON A. BLOUNT and CHARLES M. PADULA, both citizens of the United States, residing at 5 Worcester, in the county of Worcester and Commonwealth of Massachusetts, have jointly invented a new and useful Improvement in Polishing-Wheels, of which the following is a specification.

10 Our invention relates to a polishing wheel for polishing the heels of boots and shoes, and comprises improvements in construction by which the security, ease and rapidity of the attachment of the necessary waxed cloth 15 to the periphery of the wheel are greatly increased, and the assembling of the several parts facilitated, and it consists in the construction and arrangement of parts as hereinafter described and pointed out in the 20 annexed claims. We attain these objects by the mechanism illustrated in the accompanying drawings, in which—

Figure 1 is a top view of a polishing wheel embodying our invention. Fig. 2 is 25 an end view of our improved polishing wheel. Fig. 3 is a central vertical sectional view on the line 3—3, Fig. 2. Fig. 4 is a 30 sectional view on line 4—4, Fig. 3, and Figs. 5 and 6 are perspective views of the rings or washers detached, by which the waxed cloth 35 is held upon the periphery of the polishing wheel.

Similar reference characters refer to similar parts in the different figures.

35 The polishing wheel is supported upon a standard 1 to which is attached a heating shell or steam chest 2, segmental in form and provided with a horizontal bottom 3. Connection between the steam chest 2 and the 40 standard 1 is obtained by an arm inclosing steam passages 4 and 5 communicating with the steam chest 2 and arranged one above the other, as shown in Fig. 3. A steam supply pipe 6 communicates with the upper 45 passage 4 by which the steam chest is heated, and an exhaust pipe 7 is connected with the lower passage 5 through which the water of condensation, collecting upon the horizontal bottom 3, escapes.

50 Inclosing the steam chest 2 and supported upon the end of a rotatable shaft 8 journaled in bearings, not shown, is a polishing wheel constructed as follows:—Mounted upon the end of the shaft 8 is a hub 9 attached to the

shaft by a pin 10. An annular shell 11 divided diametrically is clamped upon the cylindrical hub 9 by bolts 12 passing through radial arms 12^a. The shell 11 is held from longitudinal movement by flanges 13 and 14 at either end of the hub. The flange 14 at 55 the inner end of the hub is provided with notches 15, Fig. 4, arranged to receive pins 16 held in the annular shell 11, by which the rotation of the hub 9 is communicated thereto.

65 The annular shell 11, when clamped upon the hub 9 and inclosing the steam chest 2, is provided with an outer rim or periphery 17 shaped to fit the curvature of the boot or shoe heel and covered by a cloth 18 which, in 70 the operation of the polishing wheel, is filled with wax. The cloth 18 is stretched over the periphery of the polishing wheel with its edges brought against its sides, and is secured in position by means of washers 19 75 and 20, which are placed over the edges of the cloth and press them against the sides 21 and 22 of the polishing wheel.

A pair of collars 23 and 24, one of which 80 is shown in Fig. 5, are placed in contact with the outside of the washers 19 and 20. The collars 23 and 24 are constructed in halves hinged together at 25, which permits them to be opened and applied to the outer surface of the polishing wheel. The collars 85 23 and 24 are also provided with cam surfaces 26 on their inner sides, arranged to engage lugs 27 projecting radially from the annular shell 11. The washers 19 and 20 are provided with notches 28 to provide for the 90 passage of the washers over the lugs 27, when a partial rotation of the washers will prevent their removal. The collars 23 and 24 are provided with spanner holes 29 to enable them to be rotated with their cam 95 surfaces 26 in contact with the lugs 27, and thereby pinch the cloth 18 against the sides 21 and 22 of the polishing wheel.

The several parts of the polishing wheel are readily assembled as follows:—The 100 washer 19 is slipped over the steam chest 2 and the washer 20 is slipped over the hub 9 of the shaft 8. The standard 1 is then fastened in position relatively to the end of the shaft 8 and the halves of the annular shell 11, forming the polishing wheel proper, are placed over the steam chest 2 and clamped upon the hub 9 by the clamping bolts 12, by

which the annular shell 11 is securely held upon the hub 9 with the pins 16 projecting from the annular shell 11 inserted in the notches 15 of the flange 14 of the hub. The cloth 18 is then drawn over the periphery of the polishing wheel and the washers 19 and 20 brought into contact with its edges. The halved collars 23 and 24 are then applied against the washers 19 and 20 and are rotated until the edges of the cloth are firmly pinched against the polishing wheel. Steam is admitted to the steam chest 2 and the shaft 8 is rotated, rotating the polishing wheel freely out of contact with the steam chest 2.

We claim,

1. The combination with a rotatable shaft, of a hub having upstanding annular end flanges, secured to said shaft, one of said flanges having a pair of diametrically opposite notches in its periphery, a two part annular shell, inclosing a concentric chamber, carried by said hub, each section of said

shell having opposing radial arms clamped together between the flanges of said hub, and each section provided with a pin engaging one of the said notches in said flange, and a steam shell supported within said chamber.

2. The combination, with a fixed supporting member, of a steam shell supported thereby, a rotatable shaft, a two part annular shell inclosing a chamber for the reception of said steam shell, one end of said chamber being open for the passage of said fixed supporting member, the sections of said annular shell at the other end of said chamber having opposing radial arms clamped together and supported from said shaft, and means for rotatably connecting each of said sections to said shaft.

Dated this tenth day of November 1910.

ARLINGTON A. BLOUNT.
CHARLES M. PADULA.
